UNITED STATES PATENT OFFICE.

WILLIAM HAMILTON WILSON, OF NORBITON, ENGLAND.

PRODUCTION OF HIGH-TENSION DISCHARGES.

1,320,300.

Specification of Letters Patent. Patented Oct. 28, 1919.

Application filed June 1, 1914. Serial No. 842,270.

To all whom it may concern:

Be it known that I, WILLIAM HAMILTON WILSON, a subject of the King of Great Britain, residing at 12 Cobham road, Norbiton, in the county of Surrey, England, have invented new and useful Improvements in the Production of High-Tension Discharges, of which the following is a specification.

This invention relates to improvements in 10 the utilization of condensers in apparatus for the production of high tension discharges.

In one aspect, viz., when specially considered with reference to its application to existing types of apparatus, the invention rests in controlling the rate of discharge of the condenser by including it in the high tension circuit of what is hereinafter termed a buffer transformer, through which its energy is conveyed to the devices to which in older arrangements the condenser was directly connected.

But the invention particularly lends itself to the development of certain new types of apparatus, in which the charge of a condenser is used to supplement the supply from a prime source, such as a battery, to a high tension transformer. In these forms of apparatus the condenser is still included 30 in an oscillatory circuit made up of itself and, say, the high tension winding of a buffer transformer, and its rate of discharge is governed by the capacity and effective inductance of this circuit.

When so used the condenser discharge in oscillating in the condenser circuit, superposes an oscillatory current upon that supplied from the main source, so causing the resultant current to be at times zero or negative in value. Where a direct current prime source is employed advantage may be taken of this effect by causing disconnection from the prime source to occur when the resultant current has a small or a negative value 45 so that sparking is avoided.

Examples of embodiments of the invention are illustrated by diagrams of connections in the accompanying drawings.

Figures 1-7 show a condenser operating 50 through a buffer transformer to supplement a prime source in supplying a high tension transformer,

Fig. 2 showing the buffer transformer as an auto-transformer.

Figs. 3 and 4 illustrating different means 55 of varying the power supplied through the buffer transformer, and

Figs. 5, 6 and 7 showing modifications of 60 the simple arrangement of Fig. 1 for special purposes.

Fig. 8 shows an apparatus in which the whole of the supply to a high tension transformer is by way of the condenser oscillatory circuit.

Figs. 9, 9^a, 10 and 11 are instances of the 65 general use of a condenser combined with a buffer transformer in place of a simple condenser.

The arrangement of Fig. 1 is typical of the embodiment of the invention in certain 70 new forms of apparatus in which the condenser is used to supplement the discharge of the battery or other prime source through a high tension transformer for the purpose of producing high tension discharges. 1 75 and 2 are the high and low tension windings of the transformer to be supplied. The former may be connected to any work circuit, for instance to a wireless telegraphic or a Röntgen ray apparatus. The primary 80 winding 2 is joined across the battery 3 in series with an interrupter 4 preferably of a rotary type and also in series with the primary or low tension winding 5 of a second transformer hereinafter referred to as the 85 buffer transformer. The secondary 6 of this buffer transformer has connected across it the condenser 7, the charge of which is to be employed to supplement the current from the battery 3. The secondary winding 6 90 and condenser 7 form together an oscillatory circuit the frequency of which may, for instance, be from fifty to one hundred; but this is designed according to the frequency of discharge required, and therefore 95 in some cases may exceed six hundred.

When, for the purposes of wireless telegraphy the high tension transformer is connected to a condenser, it is convenient to have the natural frequency of the buffer 100 transformer secondary circuit the same as that of the secondary circuit of the high tension transformer. The operation of this apparatus is substantially as follows.

When the contact maker 4 completes the circuit of the battery 3 through the windings 2 and 5 the condenser 7 is charged as the current rises in an oscillatory manner in the primary winding 5. Upon the interruption of the primary circuit by the interrupter 4 this charge continues to oscillate in the circuit 6, 7 but now at a rate dependent on the natural frequency of the circuit. The interrupter 4 presently closes the primary circuit a second time. The dimensions of the interrupter, its speed, and the setting of its brushes, should be such that this completion occurs when the condenser 7 is fully charged preferably for the first time in the opposite direction to its initial charge. The discharge of the condenser through the secondary winding 6 then produces an electro-motive force in the primary winding 5 which assists that of the prime source 3 in passing current through the primary 2 of the high tension transformer. It is this current which produces the desired high tension secondary discharge in the winding 1. After this discharge has taken place, the condenser becomes re-charged again to the same sign as at first, by the E. M. F. induced in the primary circuit as its magnetic fluxes fall, this E. M. F. being in the same direction as that of the supply.

It will be noted that in effect the condenser 7, or rather the oscillatory circuit 6, 7 superposes upon the current of the prime source 3 in the primary circuit, an oscillatory current which sometimes assists and sometimes opposes a current that would otherwise be supplied by the battery. The setting and dimensions of the interrupter 4 should be such that the primary circuit is broken when the primary current (due to the battery and the superposed oscillatory E. M. F.) is zero or a minimum, which minimum may preferably be negative, that is to say of opposite sign to the normal current from the battery. This minimum current is reached approximately when the condenser 7 is charged to the maximum potential it attains before reversal of the sign of its voltage. At this time the energy stored inductively in the primary circuit is a minimum, and therefore does not produce sparking during interruption.

It may be noted that the charge given to the condenser is not solely dependent on the voltage of the source of the supply and the ratio of transformation of the buffer transformer; the condenser also ultimately receives before interruption energy which has been stored magnetically in the core of the high tension transformer, or, possibly, of the buffer transformer.

It is apparent that the condenser 7 need not operate upon the primary circuit through a two-coil transformer. In Fig. 2

it is shown as connected across an inductance 8 in series with the primary 2 of the high tension transformer, which inductance forms in effect an auto-transformer. It must be remembered that the timing of the contact maker in the manner already described is essential to the proper working of the apparatus. Apparatus connected as shown in Fig. 2 has been employed for gas lighting, but with a simple vibratory interrupter in place of the timed contact maker 4; but obviously without the timing described it is impossible to secure the supplementing of the supply by the condenser discharge, or the reduction of the supply current to zero before interruption.

It may here be noted that in the figures thus far described as in those about to be described, the introduction of tapping points upon the various windings of the transformers is generally possible for the purpose of varying the ratio of transformation or the amount of inductance in either circuit and so forth.

When apparatus such as illustrated in Figs. 1 and 2 is required to supply varying amounts of power, as, for instance, may be necessary in its application to wireless telegraphic apparatus, it may conveniently be modified as shown in Fig. 3. The secondary circuit 1 of the high tension transformer is there indicated as connected through small spark gaps to a main spark gap 10 included in the closed circuit 11 of the wireless apparatus. The secondary 6 of the buffer transformer is, as before, connected with a condenser 12, but in this case the capacity in the circuit is made variable in any desired fashion. As illustrated, other condensers 13, 14 are provided which may be brought into circuit in parallel with the condenser 12 by means of a switch 15. This variation in the capacity of the secondary circuit of the buffer transformer will clearly put this circuit more or less out of tune or rather out of synchronism with the interrupter. The result is that the E. M. F. induced in the primary circuit by the discharge of the condenser may be made to a greater or less extent effective in supplementing the prime source, and so the power delivered to the high tension transformer may be varied without substantial diminution in the efficiency of the apparatus as a whole.

It will at once be apparent that when variation of the spark frequency is not objectionable the same result could be brought about without variation of the capacity if the speed of the interrupter were made variable.

A third method of securing such adjustment appears in Fig. 4 where a variable inductance 16 is shown in the primary circuit

in series with the primary windings 5 and 2. The variation of this inductance varies the time required to charge the condenser 7, and also varies the amount of energy stored 5 in the inductance of the primary circuit from the prime source.

If the apparatus is to be used for the supply of a vacuum tube for the production of Röntgen rays it is important that the 10 inverse E. M. F. should be reduced to as small a value as possible. This is conveniently done by the arrangement of Fig. 5. An additional brush is provided upon the contact maker, the function of which is 15 to short-circuit the primary winding 2 of the high tension transformer at a suitable interval after connection to the mains so that practically no back E. M. F. may be injected into the secondary circuit 1 which 20 is indicated as closed upon a vacuum tube 17.

This arrangement may advantageously be combined with that of Fig. 4, the inductance 16 then serving to store a certain proportion 25 of energy in place of that which would have been stored by the high tension primary now short-circuited.

When the load upon the secondary of the high tension transformer is very variable 30 a little trouble may be occasioned by the energy which is accumulated in the core of the high tension transformer. Fig. 6 provides for obviating this by connecting into the oscillatory circuit an additional winding 35 18 upon the core of the high tension transformer by which means the energy stored in this core can be directly taken up into the oscillatory circuit.

Fig. 7 shows another variation of the 40 apparatus for its application to wireless telegraphy. An inductance 19 not upon the core of the high tension transformer can be connected in parallel with the primary of the high tension transformer by means of 45 a key 20 so bringing about a variation in the power transmitted to the secondary circuit of the high tension transformer and thence to the antenna of the wireless apparatus.

50 Fig. 8 is a simple form of apparatus substantially analogous with Fig. 1 but differing in the fact that all the energy of the prime source reaches the high tension transformer by way of the oscillatory circuit. For in this instance the primary winding 55 21 of the high tension transformer is included in the oscillatory circuit with the secondary winding 22 of the buffer transformer and of its condenser 23. The primary circuit connected with the supply contains only the primary winding 24 of the 60 buffer transformer and the interrupter 25.

In this case the discharge of the condenser takes place directly through the pri-

mary of the high tension transformer and 65 is supplemented by the E. M. F. induced in the secondary of the buffer transformer by the prime source. The rate of discharge of the condenser is still being controlled by means of an oscillatory circuit, but the frequency of this differs from its natural frequency inasmuch as its effective inductance is modified by the current in the primary winding.

In analogous fashion the condenser may 70 be inductively or directly associated only with the secondary circuit of the high tension transformer.

But there are many forms of apparatus already in existence in which the charge of 75 a condenser is employed to supply a high tension transformer, and the invention is generally applicable to these by the substitution for the simple condenser of a condenser with a buffer transformer constituting 80 an oscillatory circuit from which energy is transferred at the desired rate to the apparatus to be supplied. It is again to be noted that this control frequency will depend upon, and can be varied by varying, 85 the coupling of the buffer transformer. In the simplest case the condenser is charged directly from a prime source and then by means of a rotary contact or the like disconnected from the source and connected 90 to the primary winding of the high tension transformer. Now the number of turns of 95 wire that can be provided upon the secondary of such a high tension transformer is limited by practical considerations. 100 When this limit is reached further increase of the ratio of transformation can only be effected by diminution of the number of turns in the primary. But if this diminution is carried very far the oscillatory circuit 105 made up of the condenser whose charge is to be utilized and the primary winding has a high natural frequency, which is further increased by the reaction of the secondary current, and the rapid change of 110 flux which ensues upon the discharge of the condenser causes very considerable losses in the core of the transformer no matter how finely it may be subdivided. Moreover, on 115 the connection of the condenser to the primary winding, the discharge current attains its maximum value in such an exceedingly brief space of time that, with a large amount of energy in the condenser, the connection cannot be made sparklessly. According to 120 the present invention therefore a condenser which it is desired to utilize in this manner is connected with the high tension transformer not directly but through a buffer transformer the high tension winding of 125 which is in the circuit of the condenser while the low tension winding, that is to say that with the fewer number of turns, is con-

5 nected across the primary of the high tension transformer. By this means the inductance in the circuit of the condenser is increased so as to increase the periodic time 10 to such a value that the iron losses are not too important; while the ratio of transformation in the high tension transformer can be adjusted over a much wider range than was hitherto possible. The buffer transformer 15 may conveniently have a transformation ratio of about 10:1, but this may be varied according to the particular purpose in view.

In another known arrangement, which is 20 shown modified according to the present invention in Fig. 10, the condenser is charged by connection across the source of supply 33 in series with the primary winding of the high tension transformer and an inductance 25 34 so that oscillations occur by which at least a portion of the energy initially stored in the inductance surges into the condenser and can then be rapidly discharged through the primary of the transformer by the completion 30 of a contact at 35 which cuts out the inductance and source of supply. Here again the buffer transformer 5, 6 is substituted in the condenser circuit for the high tension transformer 36, 37 but with the same 35 difference as before, viz., that it is the winding of the buffer transformer with the greater number of turns that is in the condenser circuit.

In another known system, shown modified 40 in Fig. 11, a condenser 38 is joined in parallel across an inductance 39 and the primary of the high tension transformer joined in series, and this completely closed circuit is charged by connection to a prime source. 45 It is then separated from the source and the energy allowed to oscillate, and when the energy is in the condenser the inductance is short-circuited, these operations being performed by a contact maker 42. This may be modified in precisely similar fashion by substituting the buffer transformer 5, 6, for the high tension transformer 40, 41.

A similar result may be obtained by the use of the apparatus illustrated in Fig. 9. 50 The condenser 26 is connected across the high tension winding 27 of a transformer or auto-transformer, these being, as indicated in Fig. 2 possible alternatives for all the systems herein described. The low tension winding 28 of the transformer is connected in series with the contact maker 29 across a prime source 3. By the aid of an additional brush on the contact maker 29 a portion of the transformer winding 28 is 55 connected at a suitable interval after interruption across the primary 30 of the high tension transformer 30, 31. It is then desirable, particularly for X-ray work, to break the circuit of the primary of the high ten-

65 sion transformer the instant the condenser has discharged for the first time, so that no inverse E. M. F. is imposed upon it. As shown at 43 in Fig. 9^a a condenser may be joined across the contact which the extra brush makes to lessen sparking which may 70 arise from the residue of energy left in the transformer cores.

75 As shown at 44 in Fig. 1^a a condenser may similarly be joined across the contact maker in such apparatus as is first above described, so that sparking is not caused by the energy remaining in the core of the high tension transformer at times of light load.

80 Where in any of the systems described an alternating current source of supply is used if it is desired that the high tension discharges shall be unidirectional, the contact maker must be designed to connect the apparatus in opposite directions to the mains in successive half waves of E. M. F. 85

It will be understood that the above are examples only of the application of the invention and do not delimit its whole scope.

What I claim is:

1. Apparatus for producing high tension 90 discharges comprising a transformer, a supply circuit for said transformer, an oscillatory circuit associated with said supply circuit so as to be capable of taking energy therefrom and restoring it, and an interrupter in said supply circuit timed in relation to the oscillatory circuit so that the energy stored in the oscillatory circuit supplements through its oscillation the supply 95 of energy from the prime source to the transformer. 100

2. Apparatus for producing high tension discharges comprising a transformer, a supply circuit for said transformer, an oscillatory circuit associated with said supply 105 circuit so as to be capable of adding to the electromotive force therein, and an interrupter in said supply circuit timed to complete the circuit when the capacity of said oscillatory circuit is fully charged and about to 110 discharge in direction to assist the supply.

3. Apparatus for the production of high tension discharges comprising a prime 115 source, a condenser, means for repeatedly charging said condenser from the prime source, a consuming device of low impedance, a buffer transformer having a high tension winding of relatively large impedance and a low tension winding, connections between the high tension winding of said 120 transformer and said condenser, and connections between the low tension winding of said transformer and said consuming device.

4. Apparatus for the production of high tension discharges comprising a prime 125 source, a condenser, a charging circuit associated with said source and said condenser so as to charge said condenser from said

source in an oscillatory manner; an interrupter adapted to break said circuit when said condenser reaches its maximum voltage, a consuming device of low impedance, and 5 means for discharging said condenser through said consuming device when the capacity of the condenser is fully charged and about to discharge in direction to assist the charging circuit.

10 5. Apparatus for the production of high tension discharges, comprising a condenser, a prime source, a charging circuit connected with said source and associated with said condenser so as to charge said condenser 15 from said source in an oscillatory manner, a circuit connected with said condenser permitting oscillation of its charge, and an interrupter in said charging circuit but independent of said oscillation circuit, adapted 20 to break said charging circuit when said condenser reaches its maximum voltage, and to reclose said circuit when the charge of said condenser again reaches its maximum after reversal of its sign due to its oscillation.

25 6. Apparatus for producing high tension discharges comprising a prime source, a high tension transformer, a circuit for supplying current from said source to said transformer, means for introducing an oscillatory current into said supply circuit, and means for interrupting the connection to said source when the energy residing in the inductance of said supply circuit is of small 30 value.

35 7. Apparatus for producing high tension discharges, comprising a prime source, a high tension transformer, a supply circuit connecting said source with said high tension transformer, an oscillatory circuit adapted to exchange energy with said supply circuit, means in timed relation with 40 said oscillatory circuit for interrupting the supply circuit, and means for varying the proportion of energy transferred from said 45 oscillatory circuit to said transformer.

8. Apparatus for the production of high-tension discharges comprising in combination a source of supply, a high-tension transformer, connections between the primary 50 winding of said transformer and said source, an oscillatory circuit inductively

associated with the circuit of said source and the primary winding of said transformer and an interrupter independent of 55 said oscillatory circuit and timed to cut off said source when the latter is supplying substantially zero current.

9. Apparatus for the production of high tension discharges comprising a condenser, a high tension transformer, a buffer transformer connected with said condenser and said high tension transformer and forming with said condenser an oscillatory circuit, and an interrupter in the high-tension, 65 transformer circuit independent of the connection of said condenser with the buffer transformer, adapted to operate in timed relation with said oscillatory circuit.

10. In apparatus for the production of 70 high-tension discharges, the combination of a prime source, a consuming device embodying means for obtaining high tension, a transformer having its low-tension winding connected to and adapted to supply said consuming device and a condenser connected to said prime source and to the high-tension winding of said transformer.

11. Apparatus for the production of high-tension discharges comprising a prime 80 source, a condenser, connections between said prime source and condenser, a timed interrupter in said connections, a high tension transformer, and a step-up buffer transformer in circuit with said condenser having its winding of smaller number of turns connected to the high tension transformer.

12. In apparatus for the production of high-tension discharges, the combination 90 of a source of supply, a high-tension transformer, an interrupter, means for connecting the primary winding of said transformer in an oscillatory circuit with said source of supply and means independent of said interrupter permitting oscillation of 95 stored energy.

In testimony whereof I have signed my name to this specification in the presence of two subscribing witnesses.

W. H. WILSON.
